Oliver S. Barnum

UNITED STATES PATENT OFFICE.

OLIVER S. BARNUM, OF ALHAMBRA, CALIFORNIA.

SHADE-ADJUSTER.

1,311,372.

Specification of Letters Patent. Patented July 29, 1919.

Application filed June 30, 1916. Serial No. 106,817.

To all whom it may concern:

Be it known that I, OLIVER S. BARNUM, a citizen of the United States, residing at Alhambra, in the county of Los Angeles and State of California, have invented new and useful Improvements in Shade-Adjusters, of which the following is a specification.

My invention relates to improvements in shade adjusters, more particularly for window shades which are mounted upon spring rollers and upon which the same are wound or rolled up by action of a spring, and from which the same are unwound or unrolled against the action of such spring. These rollers are commonly known as the Hartshorn type of shade rollers.

My invention relates to improvements in the suspension of such ordinary spring roller and its attached shade hereinafter called the primary roller, from an upper or secondary spring roller of like kind which is fixed in a certain working position, as at the top of a window opening, by means of 25 flexible connections adapted to be wound upon and unwound from said upper or secondary roller, and supporting the primary roller and attached shade in a new and suitable hanger for the same. By this means it 30 is possible to shift the position of the primary roller to station it at any part of the window opening, whereupon the attached shade may be unrolled from the primary roller to screen or cover any or all of the window opening as desired. By this means the upper, lower or center part of the window opening may be screened, while light may 35 pass unobstructedly and ventilation obtain through the lower, upper, or upper and lower parts of the window opening respectively.

The invention has for its objects to provide an improved adjuster of the general character stated, which will be superior in 45 the matter of simplicity, inexpensiveness of construction and assembling, durability, facility in adjustment and control, neatness and attractiveness in appearance, and a general superiority in efficiency and serviceability.

I attain these objects by the novel and useful provision, formation, construction, association and combination of parts, members and features shown in the accompanying drawings, in which—

Figure 1 is a front elevation of the com-

plete improved shade adjuster constructed and assembled to embody my invention, the primary roller and attached shade within the hanger being shown in a position relatively near the top of a window opening.

Fig. 2 is a front elevation of the left-hand primary roller engaging member of the hanger, on an enlarged scale.

Fig. 3 is a front elevation of the right-hand primary roller engaging member of the hanger, on an enlarged scale.

Fig. 4 is a rear elevation of the hanger member shown in Fig. 2.

Fig. 5 is a rear elevation of the hanger member shown in Fig. 3.

Fig. 6 is a side elevation of the hanger member shown in Fig. 2.

Fig. 7 is a side elevation of the hanger member shown in Fig. 3.

Fig. 8 is a cross section of the hanger at 19.

Fig. 9 is a front elevation of a hanger member.

Fig. 10 is a side elevation of the hanger member shown in Fig. 9.

Referring particularly to the drawings: B designates a primary shade roller of the Hartshorn type to which is attached a shade C. A designates a secondary spring roller of the Hartshorn type. F designates a hanger containing the primary shade roller B. f^1 designates a non-flexible rod, preferably of wood, connecting f^2 and f^3 of hanger F.

The secondary roller A is fixed in brackets of the usual type at the top of a window opening, having attached thereto by their upper extremities flexible connections d^1 and d^2 , designed to be wound upon and unwound from the secondary roller A in like manner as shades are wound upon and unwound from the Hartshorn type of spring rollers. d^1 and d^2 pass through the hanger F at holes 19, and meet at d^3 .

The hanger F preferably comprises a non-flexible member f^1 and left and right hand roller engaging members f^2 and f^3 . f^2 preferably comprises a metal sleeve 14 tightly fitting around the left extremity of f^1 , and a depending portion 11 formed at its extremity 16 to afford a notch adapted to receive the flattened end or tip of the standard type of shade rollers. f^3 preferably comprises a metal sleeve 15 tightly fitting around the right extremity of f^1 , and a depending portion 12 formed at its extremity 17 to receive the round end or tip of the standard type

of shade roller. Flexible connections d^1 and d^2 are attached to roller A at their upper extremity, pass through f^1 , f^2 and f^3 at the holes 19 and are there fixed by means 5 of set screw 20 in horizontal holes 18 as shown in Fig. 8, holes 18 being at right angles and forming a junction with holes 19 at or about the center of f^1 at either end, and within f^2 and f^3 . By means of the set 10 screw 20 the flexible connections d^1 and d^2 may be readily lengthened or shortened above hanger F, thus providing a simple and effective method of insuring a horizontal position of hanger F at all times.

15 The set screw 20 also serves to fix sleeves f^2 and f^3 rigidly to rod f^1 .

f^4 preferably comprises a semi-convex rubber disk which may be fixed to the right and left ends of the connecting member f^1 20 by means of screw 21 or otherwise, for the purpose of preventing damage to frame of window opening by contact with F or any member thereof.

The method of operating, use and advantages of the invention will be readily understood from the foregoing description taken in connection with the drawings and the following statement:

A horizontal position of hanger F, being 30 essential to proper operation of shade C, may be secured by shortening or lengthening d^1 or d^2 by releasing screw 20 and moving said flexible connections as necessary, then tightening screw 20 to compress d^1 or 35 d^2 within hole 19. When hanger F is in proper horizontal plane, its position relative to secondary roller A and window opening may be readily changed by operation of roller A by means of d^3 in like manner as 40 a shade is raised or lowered on standard type of spring shade rollers, since flexible connections d^1 and d^2 are wound thus upon and unwound from secondary roller A.

I am aware that prior to my invention window shade adjusters have been made 45 with primary and secondary rollers and means of connection between the same and therefore do not claim such a combination broadly, but do claim

In a window shade adjuster of the class 50 described, the combination of a fixed spring-actuated shade roller of the Hartshorn type; a plurality of flexible members depending therefrom and designed to be wound upon said roller by the action of said spring and 55 unwound therefrom, against the action of said spring; a traveling hanger held suspended by said flexible members and consisting of an adjustable rod and terminal 60 roller engaging members at each end thereof, each of said terminal members comprising a tightly fitting sleeve surrounding an end of said adjustable rod, and a dependent portion formed to engage a spring-actuated shade carrying roller of the Hartshorn type; 65 each of said flexible members being attached to said hanger by means of a perforation or passage transversely through a sleeve of a terminal member and part of said rod therein, through which said flexible member 70 passes, and a transverse threaded hole with suitable set screw therein, said hole being at right angles to opening into but not passing beyond said passage, allowing said set screw to impinge upon and compress said 75 flexible member within said passage; said flexible members being united beyond said passages to form a pendent cord below said hanger.

In testimony, whereof, I have signed my 80 name to this specification in the presence of two subscribing witnesses.
